RECOIL-ABSORBING DEVICE FOR FIREARMS.

1,333,403.

Specification of Letters Patent.

Patented Mar. 9, 1920.

Application filed March 22, 1919. Serial No. 284,454.

To all whom it may concern:

Be it known that we, NORBERT JULES ANDRÉ GALLIOT, a citizen of the Republic of France, and a resident of 3 Rue Auguste 5 Bailly, Courbevoie, France, and GEORGES HENRI LOUIS GASTON BORY, a citizen of the Republic of France, and a resident of 17 Rue de la Trémouille, Paris, France, have invented a new and useful Recoil-Absorbing 10 Device for Firearms, of which the following is a specification.

The present invention relates to an improvement in the recoil-absorbing device for fire-arms which consists of a divergent 15 or convergent-divergent expanding nozzle fixed to the end of the barrel of the fire-arm and co-axially thereto so as to increase the kinetic energy of the gases which are then turned aside and directed externally to- 20 ward the rear by means of a fixed guide-vane connected to the nozzle and generated by the revolution of an arc around the axis of the latter.

A recoil-absorbing device of this kind 25 for fire-arms is described and represented in our United States patent application, filed April 10, 1918, Serial Number 227,790.

It has been found that the gases directed back in a direction more or less oblique in 30 relation to the axis of the fire arm, have retained a portion of their velocity and constitute an inconvenience or even a danger for the personal serving, or the user of, the fire-arm provided with this device.

The present invention allows the elimination 35 of this inconvenience by transforming the conical stream of gas having a rapid translatory movement directed substantially backward, into a flow of vortices in which 40 the molecules of gas possess a rotary or eddying motion in a zone perpendicular to the axis of the fire-arm, this transformation taking place in the vicinity of the orifices by which the gases leave the nozzle.

For this purpose, the guide-vane which 45 serves to deflect the gaseous streams is given a doubly curved shape, of which the point of inversion or contrary-flexure lies at the intersection with the generating arc of the 50 vane of a straight line making an angle of approximately 35 to 60 degrees with the internal generatrix of the nozzle starting from the front extremity or lip of the latter.

The accompanying drawing shows by way

of example in axial section a form of construction of the improved device.

The convergent-divergent nozzle a , screwed upon the threaded extremity b^1 of the barrel b of the fire-arm (rifle, machine-gun, cannon or other) in prolongation of the axis of the latter, allows of obtaining a suitable expansion of the gases from the propellant charge, which in this way acquire a considerable speed; an obturator c , screwed inside a threaded cylindrical ring 55 or sleeve a^1 forming the end of the nozzle, is provided with a central cylindrical bore c^1 for the passage of the projectile, this bore c^1 having grooves c^2 so as to prevent or reduce considerably the escape of gas during 70 the moment when the projectile is passing through this bore, with sufficient clearance for the projectile not to be influenced during its passage. The obturator comprises on the side facing the fire-arm, a gullet c^3 75 generated by the revolution of a parabolic arc around the longitudinal axis $x-y$ of the nozzle and of the barrel; there is obtained in this way an arrangement analogous to a turbine-vane or guide-blade which 80 deflects the streams of gas at their maximum speed with the least possible friction. The rear edge of the nozzle a also has an analogous curvature at a^2 starting from the front extremity or lip of the latter, that is 85 from the point A.

The streams of gas escape to the exterior through orifices a^3 formed in the nozzle and separated from each other by solid parts so shaped as to present the least possible resistance to the flow of the gases; the reaction upon the guide-vane due to the kinetic energy of the gases operates to reduce the force of recoil of the fire-arm and may even 90 balance it.

Instead of giving to the arc, which generates the guiding surface by revolution around the axis $x-y$ of the barrel and of the nozzle, a parabolic shape according to the single curve B C D, as in the earlier specification mentioned above (which causes the gases to be rejected backward in a direction oblique in relation to the axis $x-x$) this arc is given a double curvature B C D ^{1} ; the portion B C of the parabolic curve has been retained up to the point C, but this arc is continued by a curve of opposite direction C D ^{1} ; the point C where the inversion of the curve 95 100 105

takes place is determined by the intersection with the parabolic curve B C D of a straight line making at A an angle α of 35 to 60 degrees with the internal generatrix of the 5 nozzle.

The curve B C D¹ thus obtained instead of continuing around or developing the lip α^2 of the nozzle a , leaves between the nearest points of this lip α^2 and of the guide surface 10 c , between the planes perpendicular to the axis $x-y$ passing through these points, an appreciable space for the passage of the gaseous streams.

With a guide-surface presenting this 15 double curvature, there is produced the following effect: The gases reaching the vane with their maximum speed are changed in direction upon the part B C of the curve which tends to deflect them backward—that 20 is toward the men serving the gun; when they reach the curve C D¹ there are formed in the gaseous streams vortices and eddies in such a way that the gases escape through the orifices α^3 in an eddying flow, which 25 extends and maintains itself in a comparatively localized zone substantially perpendicular to the axis $x-y$ of the fire-arm near these orifices α^3 ; the operation of the device as recoil-absorber is in no way affected. 30 It has been found that when the angle α is less than 35 degrees, the operation diminishes as regards the reduction of the recoil; beyond 60 degrees, the result is better than with an enveloping guide-vane of the single 35 curvature B C D but the eddying of the gaseous streams is less energetically produced.

It is evident that in every particular case there should be considered, according to the 40 type of fire-arm, caliber, etc., the most favorable shape for the doubly-curved arc of the guide-vane, the dimensions of the nozzle, etc.

Having now particularly described and as- 45 cerned the nature of our said invention

and in what manner the same is to be performed, we declare that what we claim is:—

1. A recoil deadener for guns comprising an expansion nozzle secured in extension of and co-axial with the gun muzzle, an end closure for the nozzle having a central opening for the passage of a projectile therethrough, and a reflexed lateral gas escape channel, the discharge mouth of which is flared to direct the reflexed stream of escaping gases into a 55 zone lying substantially at right angles to the axis of the nozzle.

2. A recoil deadener for guns comprising an expansion nozzle secured in extension of and co-axial with the gun muzzle, an end closure for the nozzle having a central opening for the passage of a projectile therethrough, and a reflexed lateral gas escape channel, the forward wall of which terminates in a re- 60 versed curve serving to direct the reflexed 65 stream of escaping gases into a zone lying substantially at right angles to the axis of the nozzle.

3. A recoil deadener for guns comprising an expansion nozzle secured in extension of 70 and co-axial with the gun muzzle, an end closure for the nozzle having a central opening for the passage of a projectile therethrough, and a reflexed lateral gas escape channel, the discharge mouth of which is flared to direct 75 the reflexed stream of escaping gases into a zone lying substantially at right angles to the axis of the nozzle, the point of inversion of the curve lying at an angle of at least 35 degrees to the wall of the nozzle, and the 80 apex of said angle being situated at the lip of the nozzle.

In testimony whereof we have signed our names to this specification.

NORBERT JULES ANDRÉ GALLIOT.
GEORGES HENRI LOUIS GASTON BORY.
